(57) **CLAIM**

The ornamental design for a manifold water distribution device, as shown and described.

DESCRIPTION

FIG. 1 is a perspective view of a manifold water distribution device, as shown and described;

FIG. 2 is a second, enlarged perspective view thereof;

FIG. 3 is a front view thereof;

FIG. 4 is a back view thereof;

FIG. 5 is a right view thereof;

FIG. 6 is a left view thereof;

FIG. 7 is a top view thereof; and,

FIG. 8 is a bottom view thereof.

The broken line portion of the figure drawings is included to show portions of the article that forms no part of the claimed design.
